UNITED STATES PATENT OFFICE.

LENOX SIMPSON, OF BELLEVUE, ALLEGHENY COUNTY, PENNSYLVANIA.

KILN.

SPECIFICATION forming part of Letters Patent No. 349,755, dated September 28, 1886.

Application filed January 27, 1886. Serial No. 189,930. (No model.)

To all whom it may concern:

Be it known that I, LENOX SIMPSON, a citizen of the United States, residing at Bellevue, in the county of Allegheny and State of Pennsylvania, have invented certain new and useful improvements in Kilns, of which the following is a clear, full, and exact description.

The object of my invention is to obtain a uniform heat in all portions of the body operated upon.

The particular application of the invention is to the burning of brick, tile, and other analogous articles, and the result aimed at is a kiln of brick or tile equally burned, and consequently of uniform color throughout. I attain this object by constructing a kiln or furnace provided with a heating-chamber protected from all drafts and air-currents, and having a superposed combustion-chamber, all arranged and operated substantially in the manner hereinafter set forth.

In the drawings, Figure 1 represents a front elevation of the furnace or kiln; Fig. 2, a longitudinal section of same, and Fig. 3 a transverse section.

Similar letters of reference indicate corresponding parts throughout the different views.

Heretofore kilns or furnaces for the burning of brick, tile, &c., have been operated upon one of three principles, to wit: either, first, by an updraft, or, second, by a downdraft, or, third, by convection.

In an updraft - kiln the brick, &c., in immediate proximity to the fire-arches are subjected to an excessive heat, (far more than that required for burning,) while the brick, &c., at and near the top of the kiln, from lack of heat are never properly hardened. Furthermore, the flame and products of combustion in passing upward seek to move in straight lines, and, notwithstanding the means taken for deflecting and diffusing the heat, those portions of the brick which lie between the arches must necessarily receive less heat than those immediately above the same. Even where the flames and products of combustion are conducted from external fire-places under the whole of a perforated kiln-floor, the result must in a lesser degree remain the same, for the heat must be greatest at those points near-

est the source of supply, and gradually lessen as the distance from same increases.

In the downdraft-kiln the flames and products of combustion, after leaving the tops of the supply-flues, move in as nearly as possible straight lines toward the openings in the floor connecting with the stack. The top brick nearest the flues will therefore receive the greatest amount of heat, while those brick which lie near the center of the kiln and those near the floor will receive less.

In a kiln heated by convection—i. e., a close kiln heated at the bottom—the heated air traverses the kiln in curvilinear currents, starting at those points where there is direct application of the fire, proceeding upward, and returning where the direct application of the heat is least perceptible. The brick therefore will be burned hardest and darkest immediately above the fire-arches, less toward the top, and least near the bottom between the arches. Finally, it is obvious that whether a draft or current be up or down or circuitous, the heat must always be greatest near those points from which the drafts begin and least at those points where the drafts fail to penetrate. In view of these facts, the desirability of dispensing altogether with drafts or currents suggested itself. The only means of accomplishing this is to apply the heat from above and confine the brick, tile, or analogous material within a chamber having closed sides and bottom, and protected from the currents necessarily formed in the combustion-chamber.

A is the furnace or kiln, whose heating or working chamber *a* is cut off from all ingress of air from the sides and bottom. A door or arched opening, *A'*, is provided through which the chamber is filled. This door is hermetically sealed before the fires are lighted.

B is an arched chamber raised a sufficient distance above the level of the top of chamber *a* to allow ample room for combustion. The object of this construction is to allow room for the passage of the flames and products of combustion, without said flames, &c., impinging upon the contents of chamber *a*.

C are the bridge-walls, from which extend inwardly the deflectors *c*. Instead of the de-

fectors *c* a floor, covering the space between and that occupied by the deflectors, may be used. This floor would be provided with oblique openings, which, while not preventing the downward transmission of heat through the air, would cut off all radiated and reflected heat. The object of the deflectors is to deflect the centrifugal currents toward the center of the arch.

10 D are two fire-places situated at either end of the kiln, and connected by throats or flues *d* with the combustion-chamber *B*.

In the bridge-walls *C* zigzag air-passages *c'* are formed, which open, on the one hand, into the external air, and, on the other, into the combustion-chamber *B* at the top of the bridge-walls. By the foregoing means a current of hot air is induced and the products of combustion and smoke consumed in chamber *B*.

20 E is the flue connecting with the stack.

Dampers *f g h*, situated in flues *d E*, and air-passages *c'* regulate the heat within the combustion-chamber. One or more peep-holes are left in the walls of chamber *a*, near its top and above the tops of the bricks to be burned, as shown at *a'*.

It will be understood that the construction described is susceptible of great variation. Thus if gas or oil be used as fuel, the fire-places and air-flues would be dispensed with, and a square combustion-chamber might be substituted for the arched one described.

The essential feature of the invention is a heating or working chamber devoid of drafts or currents and a superposed source of heat-supply.

The operation of the invention is as follows: The brick, tile, or other material to be operated upon having been placed in position with 40 in the chamber *a*, the door of the chamber is closed and sealed and the fires lighted. The fires are kept low until the brick have had time to become thoroughly dry. Afterward the fires are increased until the top bricks are 45 of a bright-red heat. It is obvious now that the heated air, being lightest, will remain at the top, and that all the air in chamber *a* will be graduated in temperature from the top to the bottom.

A portion of the heat from the top stratum of 50 air will be transmitted to the stratum immediately beneath, and from that to the next lower stratum, and so on until the bottom is reached. During this transmission the only change which takes place in the air within chamber *a* is its rarefaction, and this, being from above, cannot create a current. The bridge-walls are of considerable thickness, and, in connection with the constant flow of air through same prevent any perceptible heat from being transmitted from the flues to the heating-chamber. If the fire tends to become too hot, the dampers *f h* are partially closed and, if necessary, the damper *g* opened. The effect of this is to 60 reduce the heat in the combustion-chamber.

65 If the combustion-chamber appears to be cooling, the dampers may be opened wide and the

combustion thereby increased. By observing the top brick through the peep-hole and regulating the dampers in the foregoing manner the upper tier of brick may be kept at 70 the desired bright-red heat for an indefinite period. Meanwhile the heat has been slowly transmitted downward from one stratum of air to another, until finally the bottom tier of brick will also attain a bright-red heat. When 75 this point is reached, the whole body of brick will be of a uniform temperature. The fires are now drawn and the brick allowed to cool. As the cooling begins at the top and proceeds downward, by properly regulating the dampers the process of heating may be exactly reversed. In this way every brick may be made to hold its heat for an equal time, the top heating and cooling first, and the bottom heating and cooling last.

I do not broadly claim the use of an arched combustion-chamber, nor the use of a hot current of air to complete the combustion, as these features are common to various kinds of furnaces. Nor do I claim, broadly, the application of the heat to the brick from the top of the furnace downward, as this mode of applying the heat is common to all downdraft-kilns; 80 but

What I claim is—

1. The within-described method of burning brick, tile, or analogous articles, which consist in confining same in a close chamber free from drafts or currents, and heating from the top downward, substantially as and for the 100 purpose described.

2. In a brick-kiln, the air-flues *c'*, arranged in the side walls, *C*, between the chamber *a* and fire-flues *d*, as and for the purpose described.

3. In a furnace for burning brick, tile, and analogous articles, the combination, with the chambers *a* and *B*, of the deflectors *c*, as and for the purposes set forth.

4. In a furnace for burning brick, tile, and analogous articles, the combination, with the chamber *a*, of the arched combustion-chamber *B*, the top of said arch being raised above the top of chamber *a* a distance approximately equal to the diameter of the circle of which the arch forms a part, substantially as and for 110 the purposes described.

5. In a furnace for burning brick, tile, and analogous articles, the combination of the heating-chamber *a*, the combustion-chamber *B*, deflectors *c*, fire-places *D*, flues *d E*, and 120 air-passages *c'*, substantially as and for the purposes described.

6. In a brick-kiln, the chamber *a*, provided with one or more peep-holes at the top, and combined with dampers *f g h*, arranged as 125 shown, whereby the heat may be regulated by observing the top bricks and operating the dampers, as set forth.

LENOX SIMPSON.
